BASEBALL MITT OR GLOVE

Clive A. Smith, New York, N.Y.

Application October 21, 1946, Serial No. 704,555

1 Claim (Cl. 2-19)

1

This invention relates to baseball mitts or gloves and more particularly to the construction of the web between thumb and finger portions, and to the padding within the palm of the glove, which can be used for both throwing and catching, without removing the glove from the hand.

It is an object of the present invention to provide a baseball mitt having a web with a rolled leather outer edge.

It is another object of the invention to provide a baseball mitt or glove which is reversible for use with either the right or left hand.

It is another object of the invention to provide a baseball mitt with a removable padding to adapt the mitt for use with a soft ball.

It is another object of the invention to provide a baseball mitt with a crescent shaped rolled leather projection extending about the base of the front palm portion.

It is another object of the invention to provide an opened finger baseball mitt with rolled leather portions extending upwardly and around the open fingers of the glove.

According to the invention, as illustrated by the various forms to be presently described, the web between the thumb portion and the finger portion is provided on its outer edge with a rolled edge formation to prevent the slippage of the ball over the web. Also there is provided, according to certain forms of the invention, a rolled edge about the thumb and finger portions.

There is further provided according to certain other forms of the invention, a crescent shaped raised roll extending around the base of the mitt palm portion. This latter formation will help to keep the ball from sliding downwardly out of the mitt. In this latter formation, a metal spring can be extended for added stiffening. However, with all of these formations there is preferably provided filler material. Also the mitt is formed to provide an opening into which a removable pad can be extended when it is desired to use the mitt with a hard ball. Also, according to one form of the invention, there is provided a mitt with two hand openings by which the mitt can be used either on the left hand or on the right hand. The added padding can be inserted into the hand space not then being used by the hand.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a front perspective view of a preferred form of the invention.

Fig. 2 is a large cross sectional view taken through the tip end of one of the finger portions, as viewed along the line 2-2 of Fig. 1, looking in the direction of the arrows thereof.

2

Fig. 3 is a longitudinal cross sectional view taken along the line 3-3 of Fig. 1, looking in the direction of the arrows thereof.

Fig. 4 is a perspective view looking into one form of baseball mitt having the rolled leather web and a removable pad with a zipper opening thereof.

Fig. 5 is a fragmentary view in section showing the rolled leather web, the view being taken along line 5-5 of Fig. 4, looking in the direction of the arrows thereof.

Fig. 6 is a longitudinal cross sectional view showing the pad within the opening, the view being taken along the line 6-6 of Fig. 4, looking in the direction of the arrows thereof.

Fig. 7 is a front perspective view of a modified form of baseball mitt wherein there is provided at the rear of the mitt and at the base thereof, a spring reinforced leather roll of crescent shape.

Fig. 8 is an enlarged longitudinal cross sectional view of the baseball mitt shown in Fig. 7 as viewed along the line 8-8, looking in the direction of the arrows thereof.

Fig. 9 is a perspective view of another form of baseball mitt of a reversible type utilizing the rolled leather edge on the web and the mitt having a removable padding adapted to be put on opposite sides of the same depending upon whether the mitt is used on the left or right hand.

Fig. 10 is a fragmentary view, in longitudinal section, taken along the line 10-10 of Fig. 9, looking in the direction of the arrows thereof.

Fig. 11 is a front perspective view of another form of the invention including rolled leather padding around open thumb and fingers and a crescent rolled leather portion at the rear of the hand.

Fig. 12 is a longitudinal cross sectional view taken along the line 12-12 of Fig. 11, looking in the direction of the arrows thereof.

Fig. 13 is a transverse cross sectional view taken through the finger ends along line 11-11 of Fig. 11, looking in the direction of the arrows thereof.

45 Referring now particularly to Figs. 1, 2 and 3, showing the preferred form of my invention, 10 represents a mitt having a palm or ball receiving portion 11. This baseball glove 10 has a web 12 extending between a thumb 13 and a first finger 14. This web 12 has a rolled top edge 15. This rolled edge may have a filler so as to provide a fairly rigid edge formation. This rather rigid edge will relieve the web 12 of so much flexibility and will help to prevent the ball from passing off the glove through the thumb and first finger.

Surrounding the thumb portion 13, the finger portion 14 and other finger portions 16 and running in crescent-like shape about the base of the palm portion 11 as indicated at 17, there is a rolled edge formation 18 having a filler 19 which extends forwardly of the main surface portions of the glove. The

edge formation is continuous throughout the periphery of the glove and the thumb and finger portion. This formation around the fingers will receive the blow of the ball, and the portions of the glove lying over the top of the fingers need not be further padded. Thus the finger portion can have more flexibility and can be wrapped about the ball surface more easily.

The rolled edge as shown in Fig. 2 can be formed by folded strips and sewed to back strips 20' of material extending along the backs of the fingers. The joined faces of the folded strip are turned outward and sewed to the strips 20' as indicated at 21'. Holes 22' and 23' in the thumb and finger portion will permit the tops of the fingers and thumb to be exposed so that they may have direct contact with the ball, as the hand and glove is wrapped about the same. Within these holes 22' and 23' and to provide stiffness to the ends of the thumb and finger portions, leather strips 24' are folded into U-shape and secured to the sides of the portions. A space 25' is provided for receiving the hand and within the palm portion of the glove, there is connected a padding 26' covered by a layer 27' extending from the base of the finger portions to the rolled edge portion at the base of the glove as indicated at 17'.

Referring now particularly to Figs. 4, 5 and 6, 15 represents a mitt having a palm portion 16, a thumb portion 17 and finger portions 18. Between the thumb and the first finger, there is disposed a web 19 formed of two ply strips and secured to both the thumb portion and the finger. At the top of the web, there is connected a rolled leather ridge formation 20 including a filler 21 and folded leather 22 surrounding the filler and having its free ends stitched between the ply strips of the web 19 as indicated at 23, in Fig. 5. This rolled leather formation gives added strength to the web and will keep the thumb and finger apart. Additionally, the rolled leather will keep the ball from sliding over the edge of the web. The mitt is lined with a regular padding 24 which can be used when the mitt is being used for soft ball or where there is no great need for added padding. Near the open end of the glove, there is provided a zipper-controlled opening 25. Through this opening there may be inserted an extra removable padding 26 (Fig. 6) which will adapt the mitt particularly for use with a hard ball.

Referring now particularly to Figs. 7 and 8, there is shown a mitt 31 having two of the fingers joined as indicated at 32 and the web 19 with the rolled edge 20 between the thumb and the joined fingers. At the rear of the hand there is provided a rolled leather formation 33 with padding 34 and a reinforcing spring 35. This formation is of crescent shape and extends from the thumb portion 17 to the small finger portion 60 of the glove. The ends of this formation are preferably tapered as indicated at 36. In the interior of the nook, there is provided a lining 36 housing a pad 37 for protecting the palm of the hand.

Referring now to Figs. 9 and 10, there is shown a reversible type of mitt employing the features of the present invention. This mitt has the joined first two finger portions 32, the web 19 with the rolled leather edge 22, and the thumb portion 17. The outer fingers are joined as indicated at 41, and there is a web 42 extending between the joined finger portions 32 and the joined portion 41. Within the interior of the mitt there is provided two plys 43 and 44 of material 75 met 1943, page 42, in a certain left to right order.

material between which there is disposed a permanent padding 45. The hand can be inserted on opposite sides of the ply and into space 46 or space 47, depending upon whether the glove is to be fitted on a left or right hand. In the space opposite to where the hand is inserted, there may be disposed a removable padding 48 if the glove is to be used for a hard ball.

Referring now to the form of the invention shown in Figs. 11, 12 and 13. The thumb and first two fingers are provided with cup openings 51 and 52. Around these openings, there are provided rolled leather formations 53 about the thumb and 54 about the finger openings 52. The formation extends over the top of the fingers and downwardly between them as indicated at 55. The last two fingers have a joined enclosure 56. The mitt may also have a rolled leather formation 57 with padding 58 therewith extending in crescent-like fashion about the mitt front face which extends over the rear of the hand. These rolled formations serve to help keep the ball within the mitt.

While I have illustrated and described the preferred embodiments of my invention, it is to be understood that I do not limit myself to the precise constructions herein disclosed and the right is reserved to all changes and modifications coming within the scope of the invention as defined in the appended claim:

Having thus described my invention, what I claim as new, and desire to secure by United States Letters Patent is:

In a baseball glove having a thumb portion and an adjacent index finger portion with stitched seams along the length of the adjacent sides of the portions, a web extended between the thumb portion and the index finger portion, comprising superimposed layers of material having their inner edges secured in the stitched seams of the thumb portion and the index finger portion, said layers of material having their outer edges open, an elongated filler cord extended along the open outer edges of said layers of material, and an elongated length of material having its intermediate portion bent about said filler cord and its free edges secured in position between the open outer edges of said superimposed layers of material forming a ridge along the outer edges of said layers of material.

CLIVE A. SMITH.
